CLAIM

The ornamental design for a sole structure for a shoe, as shown and described.

DESCRIPTION

FIG. 1 is a front perspective view of a sole structure for a shoe showing our new design;

FIG. 2 is a front view in elevation thereof;

FIG. 3 is a rear view in elevation thereof;

FIG. 4 is a left side (lateral) view in elevation thereof;

FIG. 5 is a right side (medial) view in elevation thereof;

FIG. 6 is a top plan view thereof;

FIG. 7 is a bottom plan view thereof; and,

FIG. 8 is a rear perspective view thereof.

The broken lines depict environmental structure and portions of the sole structure that are not part of the claimed design. The sole structure illustrated is a first embodiment showing a rightfooted form of the sole structure for a shoe. A second embodiment of the sole structure is for the left-footed form of the sole structure for a shoe, which is a mirror image of the right-footed form, and which is not illustrated.
